ENGINE STARTER CONTROL

John B. Dyer, Pendleton, Ind., assignor, by mesne assignments, to General Motors Corporation, Detroit, Mich., a corporation of Delaware

Application January 23, 1933, Serial No. 653,048

9 Claims. (Cl. 123—179)

This invention relates to apparatus for controlling the starting of internal combustion engines and particularly engines of automotive vehicles.

5 Among the objects of the invention is the provision of a coordinated engine starter controller and an engine operation controller such as the throttle valve operating mechanism, whereby said engine operation controller may be operated to 10 control the engine starter, when the engine is not running on its own power. Means responsive to engine operation such as means responsive to vacuum in the engine intake manifold, are provided for automatically disconnecting the engine 15 starter control mechanism from the engine operation controller so that the starter will not be operated by the engine operation controller while the engine is running.

This object of the engine is accomplished in 20 the disclosed embodiment thereof by three coaxially pivoted levers, one connectable with a foot pedal, the other connectable with engine starter and the third connectable with a part of the engine to be controlled, such as the throttle valve. When the engine is at rest, a selecting device responsive to engine operation connects the pedal lever with the engine starter lever, but when the engine is running the selecting device moves to connect the pedal lever only with the 25 throttle lever, the starter lever then being disconnected from the pedal lever. In the disclosed form of the invention the throttle lever remains connected with the pedal lever so that, during movement of the pedal lever to control the engine 30 starter, the throttle will be opened to facilitate the starting of the engine.

Further objects and advantages of the present invention will be apparent from the following description, reference being had to the accompanying drawings wherein a preferred embodiment of one form of the present invention is clearly shown.

In the drawings:

45 Fig. 1 is a side view partly in section of the engine starter control apparatus embodying the present invention.

Fig. 2 is a view looking in the direction of arrow 2 of Fig. 1, certain parts being shown in section on the line 2—2 of Fig. 1.

50 Figs. 3, 4 and 5 are sectional views taken on the line 3—3 of Fig. 2 and show various parts in different positions of operation.

Fig. 6 is a perspective view of certain parts 55 showing their normal relation.

Fig. 7 is a view similar to Fig. 6 showing these parts arranged for operation during the running of the engine.

Fig. 8 is a perspective view, looking in the direction of arrow 8 of Fig. 9, of certain parts of

the mechanism shown in disassembled relation, said parts being coaxially arranged.

Fig. 9 is a perspective view similar to Fig. 8, said parts being viewed approximately in the direction of arrow 9 of Fig. 8.

The engine starting apparatus comprises an electric motor having a field frame 20 upon which is mounted a starter switch 21 comprising stationary contacts 22 and 23 and movable contact 24 operated by plunger 25 and held out of engagement with the stationary contacts by a spring 26. The contact 22 is provided by the head of a terminal screw 27 which is connected with a storage battery or other current source. The contact 23 is provided by the head of the bolt 28 which is connected with the windings of the motor. The motor armature 30 is supported by shaft 31 which is splinedly connected to a sleeve 32 which is connected by an overrunning clutch 33 with a pinion 34 as described in detail in the 20 William A. Chryst Patent Number 1,807,772, issued June 2, 1931. Motion is transmitted to the sleeve 32 through a spring 35 from a collar 36 which is slidable along the sleeve 32 and is prevented from removal from the sleeve 32 by a spring split-ring which is snapped into a groove 25 provided by the sleeve 32. The collar 36 receives studs 39 provided by the arms 40 of a forked lever 41 pivoted at 42 upon the gear housing 43 which is attached to the field frame 20. A coil spring 44 urges the lever 41 in a clockwise direction to retract the pinion 34 from the flywheel gear 105. The lever 41 is provided with a portion 45 for engaging the switch plunger 25. The lever 41 is provided with slots 46 and 47 which extend substantially radially with respect to the pivot 42. These slots 46 and 47 receive bolts 48 and 49, respectively, which pass through holes provided in a plate 50, the hole in plate 50 receiving the bolt 48 being round and the hole in plate 50 receiving the screw 49 being 40 elongated as shown at 51. The bolts 48 and 49 receive nuts 48a and 49a, respectively, so that, when the plate 50 is located in adjusted position with respect to the lever 41, the nuts may be tightened so that the plate 50 will be clamped to the lever 41 in the desired position of adjustment. The plate 50 carries a roller 52 pivoted upon a stud 53 attached to the plate 50.

The bulk head 60 or rear wall of the engine compartment supports brackets 61 and 62 which are welded to and support a cup-shaped case 63 (see Fig. 2). The bracket 61 and the end wall 64 of the case 63 are apertured with aligned holes for receiving a sleeve or bearing 65 provided with a shoulder 66 which is confined between flanges 67 and 68 provided, respectively, by the case 63 and the bracket 61. This bearing sleeve 65 provides a support for three coaxially pivoted levers, namely, the lever 70 which is connectable with a 60

foot pedal or other device operated by the driver, said lever being hereinafter called the pedal lever, lever 71 for operating the engine starter, said lever 71 being hereinafter called the starter lever, and lever 72 which is connectable with the engine carburetor throttle, said lever 72 being hereinafter called the throttle lever. Lever 70 is fixed to a tubular shaft 73 having splines 74. Lever 71 is attached to a hub 75 rotatable upon 10 the bearing sleeve 65. Lever 72 is fixed to a shaft 76 rotatably supported by the tubular shaft 73.

For engine starting purposes the starter lever 71 is connected with the pedal lever 70, but during the running of the engine the starter lever 71 is disconnected from the lever 70. This connection of the lever 71 with respect to the lever 70 is effected by a selector mechanism responsive to the operation of the engine. The selector 20 mechanism comprises a selector plate 80 having its hub 81 splinedly connected to the splines 74 of shaft 73. The plate 80 is shifted longitudinally of the shaft 73 by means responsive to engine suction which comprises a yoke 82 attached to a hub 83 threadedly connected with a plug 84 having a rivet shank 85 which attaches said plug 84 together with a plain washer 86 and a cupped washer 87 to a diaphragm 88 which is clamped between the interlocked flanges of two 30 metal shells 88 and 90 which are confined against a ledge 63a by a cover plate 63b secured to case 63 by screws 81. The shell 90 supports a coupling 92 having a threaded or tapped inlet 93 connectable with a pipe, not shown, leading to 35 the intake manifold of the engine. The space between the diaphragm 88 and shell 90 therefore provides a suction chamber communicating with the coupling 92. The diaphragm 88 is urged toward the left as shown in Fig. 2 by spring 40 95 located between the washer 87 and a plug 96 screwed into a threaded hole 97 in coupling 92, said plug being coaxial with the spring 95. Hence, the spring urges the selector plate 80 into the position shown in Figs. 2 and 6, in which 45 position the pedal lever 70 is connected with the starter lever 71.

In the normal position of the apparatus or position in which it occupies when the engine is at rest, the selector plate 80 is so located that 50 surfaces 100 and 101 thereof are located in the planes of lugs 102 and 103 integral with the lever 71. It is, therefore, apparent that movement of the pedal lever 70 clockwise as viewed in Figs. 1, 3 and 6 will cause the shaft 73 to 55 rotate clockwise as viewed in Fig. 3, thereby causing the selector plate 80 to move clockwise and its surfaces 100 and 101 to engage the lugs 102 and 103 of the lever 71 thereby causing the lever 71 to move clockwise as viewed in Fig. 1 and a 60 pad 104 thereof to engage the roller 52 whereupon the lever 71 will be moved counter-clockwise to cause the pinion 34 of the engine starter to engage the flywheel gear 105 of the engine and the lever surface 45 to engage the switch 65 plunger 25 to close the motor switch whereupon the motor will operate to crank the engine. Movement of the pedal lever 70 through an angular distance sufficient to cause the engine starter to operate will cause the selector plate 80 70 to move sufficiently to cause its lug 110 to engage a lug 111 of a throttle plate 112 which is attached to shaft 76 and to move said lug 111 from the position shown in Fig. 3 to the position shown at 111a in Fig. 4. This movement of the lug 111 will cause the lever 72 to move the throt-

tle to partly open position to facilitate engine starting.

When the engine becomes operative the suction produced thereby will cause the diaphragm 88 to be moved to the right thereby moving the selector plate 80 toward the right and disengaging the surfaces 100 and 101 from the lugs 102 and 103 of the lever 71. This disengagement will be facilitated by retraction of the pedal, which is instinctively released by the operator 10 when the engine starts, thereby decreasing the pressure between the surfaces 100 and 101 of the selector plate 80 upon the plugs 102 and 103 of the starter lever 71. Since the selector plate 80 engages only the throttle plate 112 during the 15 running of the engine, it is apparent that the pedal lever 70 will hereafter operate only the throttle lever.

The selector plate 80 is so shifted as to prevent reengagement of the pedal lever 70 with the 20 starter lever 71 at any time while the engine is running. When the engine is running with the throttle partly open, the suction operating upon the diaphragm 88 will be sufficient to maintain the selector plate 80 out of the path of movement of the lugs 102 and 103 of the lever 71. When the engine is operating at full load and at 25 low speed, the engine manifold suction operating on the diaphragm 88 may be insufficient to maintain the selector in retracted position against 30 the action of spring 95, and the selector plate 80 may be urged by the spring 95 against the lugs 102 and 103; but, when the throttle is wide open, the selector plate 80 will be in the position shown in Fig. 5, in which position its surfaces 100 and 35 101 are out of alignment with the lugs 102 and 103 of the lever 71. Hence, the plate 80 is not operatively connected with the lever 71. Return of the pedal lever 70 into part throttle position will cause the engine manifold suction to increase 40 and retract the selector plate from the lugs 102 and 103. It is therefore, apparent that reengagement of the selector plate 80 with the lever 71 cannot take place until the engine stops and the pedal lever 70 has been returned to normal 45 position.

The lever 70 is maintained in normal position with its stop 70a resting against the bracket 61 as shown in Fig. 1, by coil spring 120 having one end 121 bearing against the lever 70 and the other end 122 received by a hole 123 in the bracket 61 and case wall 64. The lever 71 is urged also in a clockwise direction against a stop 124 provided by the opening 125 for lever 71 in case 63, as shown in Fig. 3, by a single turn coil spring 126 having one end 127 received by a hole 128 in the bracket 61 and case end wall 64 and having the other end 129 bearing against the lever 71 in the counter-clockwise direction.

The levers 70 and 72 are provided with holes 130 and 131 respectively, which, as shown in Fig. 2, are of the same size and extend the same distance from the axis of shafts 76 and 73. While the lever 70 is in normal position with its stop 70a resting against bracket 61, the lever 72 is 60 moved manually until its hole 131 is in alignment with the hole 130 with the lever 70. A rod 65 may be pushed into these aligned holes to hold the lever 72 in position while adjusting its connection with the throttle lever.

While the form of embodiment of the present invention as herein disclosed, constitutes a preferred form, it is to be understood that other forms might be adopted, all coming within the scope of the claims which follow.

What is claimed is as follows:

1. A coordinated engine control and engine starter control comprising, in combination, three coaxially pivoted levers, namely, a pedal operated lever, a starter control lever, and an engine control lever, means for connecting the pedal lever with the engine control lever, means for connecting the pedal lever with the starter control lever, a single bearing supporting said levers, 5 a tubular housing having an end wall supporting said bearing, and means providing a closure for said housing and responsive to engine operation for disabling the connection between the pedal lever and the starter control lever.
- 15 2. A coordinated engine control and engine starter control comprising, in combination, three coaxially pivoted levers, namely, a pedal operated lever, a starter control lever, and an engine control lever, means for connecting the pedal lever with the engine control lever, means for connecting the pedal lever with the starter control lever, a single bearing supporting said levers, a tubular housing having an end wall supporting said bearing, a device for closing the opposite 20 end of said housing and comprising a suction chamber connectable with the engine intake and having a displacement member, and means cooperating with the displacement member in order to disable the connection between the pedal lever 25 and starter control lever.
3. A coordinated engine control and engine starter control comprising, in combination, three coaxially pivoted levers, namely, a pedal operated lever, a starter control lever, and an engine control lever, a tubular shaft connected to the 30 pedal lever, a tubular bearing for the shaft, a shaft journalled within the tubular shaft, a starter control lever journalled upon the tubular bearing, an engine control lever attached to the second shaft, means connecting the first and second shafts, means normally connecting the 35 starter control lever with the first shaft, and means for disabling said connection between the starter control lever and first shaft in response 40 to the engine becoming self-operative.
4. A coordinated engine control and engine starter control comprising, in combination, three coaxially pivoted levers, namely a pedal operated lever, a starter control lever, and an engine control lever, a tubular shaft connected to the 45 pedal lever, a tubular bearing for the shaft, a shaft journalled within the tubular shaft, a starter control lever journalled upon the tubular bearing, an engine control lever attached to the second shaft, 50 an axially movable member splinedly connected with the tubular shaft and connected with the second shaft and normally connected with the starter control lever, and means for moving said axially movable member so as to disconnect the 55 starter control lever from the tubular shaft in response to the engine becoming self-operative.
5. A coordinated engine control and engine starter control comprising, in combination, three coaxially pivoted levers, namely, a pedal operated lever, a starter control lever, and an engine control lever, a tubular shaft connected to the 60 pedal lever, a tubular bearing for the shaft, a shaft journalled within the tubular shaft, a starter control lever journalled upon the tubular bearing, an engine control lever attached to the second shaft, 65 an axially movable plate splinedly connected with the tubular shaft, a plate attached to the second shaft, connections between the two plates, a lug provided by the starter control lever and extend- 70
- ing toward the first plate and normally located in the plane of movement of said first plate so as to be engaged thereby, and means responsive to the engine becoming self-operative for shifting the second plate away from the starter control lever 75 to disconnect the same from the tubular shaft.
6. A coordinated engine control and engine starter control comprising a starting motor, a lever for controlling the action of said starting motor, a group of pivoted levers including a lever 10 for controlling the quantity of fuel mixture supplied to the engine and a third lever adapted to control the operation of said two first mentioned levers, mechanism normally connecting the said third lever with both of the other two levers 15 whereby actuation of said third lever will cause the starting motor to become operative and will position the mixture control lever to supply the proper amount of fuel mixture to the engine and suction operated means to disable the connection 20 between the third lever and the lever which controls the action of said starting motor when the engine becomes self-operative.
7. A coordinated engine control and engine starter control comprising a starting motor, a lever for controlling the action of said starting motor, a group of pivoted levers including a lever 25 for controlling the quantity of fuel mixture supplied to the engine and a third lever adapted to control the operation of said two first mentioned levers, mechanism normally connecting the said third lever with both of the other two levers 30 whereby actuation of said third lever will cause the starting motor to become operative and will position the mixture control lever to supply the proper amount of fuel mixture to the engine and suction operated means operable to disable only 35 the connection between the third lever and the lever which controls the action of the starting motor when the engine becomes self-operative, 40 whereby during operation of the engine said third lever is ineffective to cause operation of the starting motor, but is effective to control the mixture supply.
8. A coordinated engine control and engine 45 starter control comprising, in combination, three coaxially pivoted levers, namely, a pedal operated lever, a starter control lever, and an engine control lever, mechanism for normally connecting the pedal lever with both the engine control lever 50 and the starter control lever whereby operation of said pedal lever will effect operation of both said control levers, a bearing supporting all of said levers and means responsive to engine operation for disabling the connection between the 55 pedal lever and the starter control lever.
9. A coordinated engine control and engine 60 starter control comprising, in combination, three coaxially pivoted levers, namely, a pedal operated lever, a starter control lever, and an engine control lever, mechanism for normally connecting the pedal lever with both the engine control lever and the starter control lever whereby operation of said pedal lever will effect operation of both 65 said control levers, a bearing supporting all of said levers and means responsive to engine operation for disabling only the connection between the pedal lever and the starter control lever when the engine becomes self-operative, whereby after the engine becomes self-operative the connection between the pedal lever and the engine control lever remains effective.
